TREATMENT OF PEAT.

1,160,463.

Specification of Letters Patent. Patented Nov. 16, 1915.

Application filed February 25, 1913. Serial No. 750,561.

To all whom it may concern:

Be it known that we, NILS TESTRUP, a subject of the King of Great Britain and Ireland, and residing at 3 Dean Farrar street, London, S. W., England, and THOMAS RIGBY, a subject of the King of Great Britain and Ireland, and residing at 61 Loretburn street, Dumfries, Scotland, have invented certain new and useful Improvements in the Treatment of Peat, of which the following is a specification.

This invention relates to the treatment of peat by such process of wet treatment of peat as apparently by chemical decomposition of some component of the peat renders its water more freely removable, for example the wet carbonizing of the same.

In wet carbonizing peat in apparatus such as has been proposed by Ekenberg (British Letters Patent No. 10834 of 1903) wherein rotating tubular elements are employed, the provision of the rotating elements is liable to be a source of substantial cost in operation, owing to wear and the need of replacement of the parts, and moreover, is a large factor in the initial cost of the apparatus.

We have observed that if, instead of providing rotating scrapers and other devices within the tubular and other elements, the peat pulp to be carbonized is forced through the apparatus at considerable velocity, it is possible by this means alone to prevent blocking and other difficulties which the rotation of the elements was intended to avoid, and that it becomes unnecessary therefore to provide such rotating elements. We have discovered, however, that the high rate of flow tends to result in incomplete carbonization due as it would appear from our experiments to the rate at which the carbonizing reaction proceeds having a limited velocity. The material requires therefore to be maintained for some appreciable period at the carbonizing temperature before it is allowed to cool by transfer of its heat to a fresh quantity of the material. It must be borne in mind, however, that such time element in the reaction is, as our experiments suggest, dependent upon the temperature which is selected for the maximum in the carbonizer, it becoming shorter with rising temperature and is also apparently dependent upon the degree of the decomposition or general nature of the peat treated. The completion of wet carbonization to the de-

sired degree can be gauged by the readiness with which the macerated pulp from the carbonizers parts from its water in a filter press or the like to give a coherent cake of relatively low water content and unaccompanied by objectionable shining up of the cloths. In operating therefore with a high rate of flow of the peat pulp as above indicated, we make allowance for the above features.

The present invention consists in a method of effecting wet carbonization of peat in which the peat is caused to flow at such a velocity through the apparatus that moving scraping or other devices become unnecessary, and in which the peat, after having been raised to the desired carbonizing temperature or thereabout, is maintained at this temperature for a sufficient period to allow the carbonization to complete itself to the desired extent.

In carrying the invention into effect, we generally arrange that the raw peat shall be gradually heated regeneratively before external heat is applied finally to raise the temperature of the material to that at which it is to be maintained while carbonizing is being completed.

The accompanying drawing shows diagrammatically in Figure 1 one form of a complete carbonizing element adapted for such regenerative heating and a vessel for retaining the heated peat; Fig. 2 shows a preferred form of baffle; and Fig. 3 shows a modified form of apparatus suitable for carrying the invention into effect.

The carbonizing element is composed of long concentric stationary tubes, say respectively of 3½ inches internal, 4 inches external and 5 inches internal diameter and for instance between 700 and 1,000 feet in total length, and which may be as shown divided into five sections or sets of tubes. Through the outer tubes, *a* and *b*, of the first two sets of tubes a hot liquid, such as the effluent from the filter presses of the installation is introduced at *c*, and passes through the tube, *a*, bend, *d* and tube *b*, in the direction indicated by the arrows, and thereafter passes to the outlet, *e* for example to any suitable waste such as the moss. The raw peat to be carbonized enters the carbonizing element by the inner tube, *f*, and flowing in a direction opposite to that of the hot effluent or other liquid receives heat from the latter and is thereby regeneratively heated. On

leaving the inner tube, *f*, by a bend *g*, the peat passes through the second inner tube, *h*, where it is further heated while its temperature gradually approaches that of the effluent entering the surrounding jacket at *c*. The partially heated peat is now conducted by a bend, *i*, to the inner tube, *j*, in which it is further regeneratively heated, but in this case by the peat which has been wet carbonized and is flowing in the opposite direction in the outer tube, *h*. As the raw peat in thus flowing through the tube, *j*, is surrounded by wet carbonized peat the temperature of which increases with decrease in the distance from the source of the wet carbonized peat, it becomes necessary to prevent radiation of heat from the hot peat. This is avoided by arranging that the colder material, after passing through the tube, *j*, is conducted by way of a bend *m*, into the outer tube, *n*, of the next tube set, the inner one, *o*, of which contains the hot wet carbonized peat and conveys the same by way of a bend, *p*, to the outer tube, *h*. In this way the colder material passing in the outer tube, *m*, forms to some extent a lagging which diminishes loss of heat.

The raw material on leaving the tube, *n*, then passes into an inner tube, *q*, and having passed to the end thereof its direction of flow is reversed, and it passes through the outer concentric tube, *r*. In this tube set the external heat necessary finally to raise the temperature of the material to that which has been selected for the maximum is supplied, this being effected in the arrangement shown by means of a steam jacket, *s*, to which steam at a pressure of about 190 lbs. per square inch is supplied, such steam being obtained, for example, from a high pressure exhaust of a high pressure steam engine supplying power for the installation, and after leaving the jacket and being otherwise utilized is returned to the steam generating plant as feed water. By thus arranging that the colder material entering this part of the carbonizer is confined to the inner tube, *q*, the advantage is obtained that the jacket wall is in direct contact with the material which is to be heated to the highest temperature. The material having now been raised to the required temperature leaves the tube, *r*, and passes by way of a conduit, *t*, into a closed vessel, *u*, which is provided with a rotating mixer, *v*, and intermediate baffles, *w*. The rate of flow of the material is by this means materially reduced, so that it remains for instance about twenty minutes although this may be substantially greater or less as indicated above in the vessel, *u*, before passing into the conduit, *x*, by which it is conveyed to the inner tube, *o*, of the regenerative part of the carbonizing element.

65 It will be understood that where in carry-

ing this invention into effect several carbonizing elements and peat retaining vessels of the type above described are employed, the hot liquid which effects the preliminary regenerative heating of the raw peat may be supplied to that regenerative part of several carbonizing elements from the same conduit, such regenerative parts in some cases being grouped together apart from the rest of the carbonizing elements. 70 A mixing vessel may be provided for each carbonizing element, or if preferred, several such elements may deliver the hot peat into the same vessel or, according to another arrangement, the mixing vessels may deliver the carbonized peat into the same conduit from which it is distributed to the carbonizing elements for the purpose of effecting regenerative heating of the incoming raw material. Those regenerative portions 80 pertaining to several carbonizers and in which hot peat pulp supplies heat may likewise be grouped together and the externally heated portions grouped in one or more steam jackets. 90

A rate of flow which we have found satisfactory for running the apparatus with stationary tubes was with a particular sample of peat pulp finely macerated and containing about 94 per cent., water 9" per second 95 to as much as 3 ft. per second or higher. We find the heat transmission per unit surface from peat to peat, and from steam to peat increases rapidly with an increase of velocity, and when working with a velocity 100 of flow of about 2 $\frac{1}{2}$ ft. per second, a steam jacket of about 100 ft. in length is suitable. The length of the tube element in which the regeneration goes on varies with the velocity 105 and the amount of heat which has to be transmitted or regenerated, and the difference in the temperature between the heat transmission surfaces. We find for instance that the length of tube element required when working with a velocity of 2 $\frac{1}{2}$ ft. per second is about 950 ft. in the regenerative portion, and in addition to the length of the steam jacket, this being with a difference of temperature on the regenerative heating surface of about 40° C. It is obvious that 110 the length of tube can be varied to suit the conditions governing this heat transmission and the amount of regeneration required. 115

It is to be observed that principal features 120 of the invention above set out are dependent upon our observation that if the peat pulp to be carbonized is forced through the apparatus at a considerable velocity, it is possible by this means alone to prevent blocking 125 and other difficulties which the rotation of the elements in former apparatus (see British Patent specifications Nos. 10834 of 1903, 6041 of 1910 and 17610 of 1911) was intended to avoid. We have further observed, however, that with such rate of flow 130

there is a tendency for incomplete carbonization and that as it would appear from our experiments, the rate at which the carbonizing reaction proceeds has a definite velocity, 5 the material requires therefore to be maintained for some appreciable period at the carbonizing temperature before it is allowed to cool by transfer of its heat to raw material entering the carbonizer.

10 The pressure which may be required in the case of an apparatus of the dimensions which have been instanced to give the pulp the desired velocity through the apparatus has been observed by us with one particular peat 15 finely macerated and containing say 93.5% of water to amount to several hundreds of pounds per square inch—800 lbs. in one particular experiment.

Although the maintenance of the heated 20 peat for the required time at the predetermined temperature has been described as effected in a vessel of a special character separate entirely from the concentric tubular system, it will be understood this is referred 25 to by way of example only and that the result may be obtained as shown in Fig. 3 by causing the peat to flow through a section of tube u' of the requisite length in which it is merely prevented from losing its heat by 30 suitable lagging means w' .

It is important in order to secure efficient 35 heat regeneration, rapid heat transmission and general economy in the working of the apparatus to insure a substantial agitation 40 within the peat pulp flowing through the apparatus, and while the rapid flow alone produces apparently the movement necessary to prevent lodgment on the walls our experiments suggest a tendency to channeling or 45 stratification in the pulp. For this reason among others we prefer to provide specific devices such as perforated baffles, *e. g.* as shown to an enlarged scale in Fig. 2, a dia- 50 phragm y with a large central orifice, in the path of the flow and at suitable distances apart these acting to produce a churning or eddying in the material. In order to prevent likelihood of deposition in the angles formed by these devices it is desirable to 55 provide coned approaches thereto as shown. Again if cross connections be provided at intervals which interchange the streams of peat from annulus to core and vice versa, each interchange will secure an agitation of the material.

An important advantage arising from alternately passing the peat passing from and into the carbonizer through annulus and core of the tube sets described with refer-

ence to the drawing is that it enables a construction to be obtained in which as with that illustrated the raw peat passes to the maximum extent through the inner tubes of the system this leading to a reduction of pressure required for propulsion owing to 60 the raw peat with the relatively high viscosity or shear on the tube walls passing through that part where the proportion of surface of wall to cross sectional area is least.

The apparatus may be constructed with 65 any desired number of concentric tubes and layers of peat flowing therein. Thus the regenerator portion may be formed of four concentric tubes in alternate ones of which flow respectively peat to and peat from the 70 carbonizer portion proper.

Having now described our invention what we claim as new and desire to secure by Letters Patent is:—

1. Process for the heat treatment of peat 80 which consists in causing the peat to travel through heating elements at such a rate that deposition of the peat in said elements is prevented by virtue of the rapid rate of flow of the peat itself.

2. Process for the heat treatment of peat 85 which consists in causing the peat to travel through heating elements at such a rate that deposition of the peat in said elements is prevented by virtue of the rapid rate of flow 90 of the peat itself, and in which the peat is maintained at or about the desired maximum temperature until the requisite degree of treatment has been attained.

3. A method of wet carbonizing peat, in 95 which the peat is heated to a predetermined temperature under pressure, maintained at about this temperature for a relatively extended period and then caused to flow through fixed tubes in which it is churned 100 at high speed at intervals by mixing devices.

4. A process for the heat treatment of peat consisting in causing the peat to flow through heat interchanging passages that by reason of the rate of flow alone deposition of the 105 peat in said passages is prevented and in disturbing said flow at intervals by baffling.

In testimony whereof we have signed our names to this specification in the presence of two subscribing witnesses.

It is hereby certified that in Letters Patent No. 1,160,463, granted November 16, 1915, upon the application of Nils Testrup, of London, England, and Thomas Rigby, of Dumfries, Scotland, for an improvement in "Treatment of Peat," an error appears in the printed specification requiring correction as follows: Page 2, line 112, for the word "of" read *in*; and that the said Letters Patent should be read with this correction therein that the same may conform to the record of the case in the Patent Office.

Signed and sealed this 24th day of October, A. D., 1916.

[SEAL.]

F. W. H. CLAY,
Acting Commissioner of Patents.
